UNITED STATES PATENT OFFICE

EMERY MIHALEK, OF CHICAGO, ILLINOIS, ASSIGNOR TO O. D. JENNINGS & COMPANY, OF CHICAGO, ILLINOIS, A CORPORATION OF ILLINOIS

COIN CONTROLLED APPARATUS

Application filed May 21, 1930. Serial No. 454,451.

The invention relates to coin-controlled apparatus and seeks to provide improved means for safe-guarding coin-controlled apparatus and devices and preventing their operation by other than coins of a predetermined value. More particularly the invention seeks to provide improved means for preventing the operation of coin-controlled apparatus by annular checks or washers, and the invention 10 consists in the features of improvements hereinafter set forth, illustrated in the preferred form in the accompanying drawings and more particularly pointed out in the appended claims.

15 In the drawings:

Fig. 1 is a view in elevation of the coin chute and associated parts, and which can be employed more particularly in connection with vending machines or other apparatus 20 and devices.

Figs. 2, 3 and 4 are detail sections on the lines 2—2, 3—3 and 4—4, respectively, of Fig. 1.

Figs. 5 and 6 are views partially in elevation and partially in section of the improved coin-controlled mechanism, with the back plate of the coin chute removed and with parts shown in shifted position to illustrate their operation.

25 Fig. 7 is a detail view in elevation, on reduced scale, of the operating shifter arm.

The improved mechanism is mounted upon a bracket or frame comprising front and back plates 10 and 11 connected together by 30 screws 12. The front plate is provided with raised or thickened portions and ribs at its edges forming a chute 13 for the admission of coins and separate discharge chutes 14 and 15. The chute section 13 communicates 35 at its upper end with an opening 16 for the insertion of coins, and the chute sections 14 and 15 communicate at their lower ends with discharge openings 17 and 18 respectively. Otherwise the chute sections formed in the 40 front plate 10 are closed by the back plate 11 and these chute sections are arranged for the passage of coins and the like edgewise therethrough.

A shaft 19 for operating the vending mechanism or other apparatus through the medi-

um of the improved coin mechanism, is journaled in suitable bearings formed in the plates 10 and 11 and an arm 20 fixed to this shaft is provided with an offset stud or abutment lug 21 (see Figs. 1 and 4) which projects 55 through an arc-shaped slot 22 formed in the back plate 11. A spring 23 connected to this arm holds it in normal position with the stud or abutment 21 engaging a stop shoulder 24 (see Fig. 4) on the back 60 plate 11.

A manually operable shifter arm is loosely mounted on the forward end of the shaft 19 and in the form shown comprises a segmental portion 25 having a hub held in place on the 65 forward end of the shaft 19 by a washer 26 and a screw 27. An extension 28 fixed to the segment 25 is provided with an offset finger piece 29 by which the shifter arm may be engaged and manually oscillated. A spring 30 70 connected to the shifter arm holds it in normal position in engagement with a stop lug 31 formed on the front plate 10. The arm is also provided with a stud or abutment lug 32 which projects laterally through an arc-shaped slot 33 formed in the front plate 10, 75 as most clearly shown in Figs. 5 and 6.

The studs or abutment lugs 21 and 32 on the operating and shifter arms, respectively, extend into and across the coin chute between 80 the plates 10 and 11 and move in arcs therein as the arms are oscillated. It is noted that the arc through which the stud 21 on the operating arm moves has a radius that is slightly shorter than that of the arc-shaped path 85 of the stud 32 on the manually operable shifter arm, so that ordinarily movement of the shifter arm will not effect the movement of the operating arm. But such movement of the operating arm is effected upon the forward stroke of the shifter arm when a proper coin is interposed between the abutment studs 32 and 21. Preferably, the stud 21 which extends through the slot 22 in the back plate extends into an arc-shaped groove 90 34 formed in the front plate, and the stud 32 extends into a similar arc-shaped groove (see Fig. 2) formed in the back plate, so as to prevent the jamming of thin coins or the like between the ends of the studs and plates. 95 100

With the parts in normal position, a coin inserted at the chute section 13 is arrested by engaging the abutment stud 32 of the shifter arm and the end of the arc-shaped fixed lug 35 formed upon the front plate 10. A coin or check so arrested is indicated in dotted lines at *a* in Figs. 1 and 6. A short arm 36 pivoted on the back plate 11 is provided with an offset 37 at its lower end which projects into the coin chute and is held in normal position by a spring 38. The normal position of this arm and offset is shown in Figs. 1 and 6, and the offset is movable as the arm swings on its pivot through an arc-shaped slot 39 formed in the back plate (see Fig. 1), and a correspondingly shaped depression 40 formed in the front plate (see Figs. 5 and 6). In normal position, the offset 37 aids in directing an inserted coin or check to the position indicated at *a* in Figs. 1 and 2. It is noted that the fixed lug 35 is so spaced from the normal position of the stud 32, that coins less than the predetermined size will not be arrested, but will pass between these parts and out through the coin section 15.

While not entirely necessary since the shifter arm will not actuate the operating arm except through the medium of an interposed coin, a latch is preferably provided for arresting the movement of the shifter arm after a limited, initial forward movement. In the form shown, this latch 41 (see Fig. 4) is pivoted on the shifter arm and is pressed by a spring 42 toward the front plate 10, with its free end extending through a square opening 43 formed in the front plate, between the fixed lug 35 and the normal position of the stud 32. In the normal position of the shifter arm, the end of the latch 41 engages the rear edge of the opening or slot 43 and is thereby held out of the coin chute. But in the absence of a coin in the position shown at *a* in Figs. 1 and 6, the end of the latch 41, upon the initial movement of the shifter arm, will move into the coin chute and engage the forward edge of the slot or opening 43 and thereby prevent any further movement of the shifter arm. However, the presence of a coin or check in the arrested position will prevent the entrance of the latch into the chute so that the forward movement of the shifter arm can be completed.

Upon the forward movement of the shifter arm, the stud 32 engages the inserted coin and moves it over the upper edge of the guide lug 35 and against the abutment stud 21 of the operating arm 20, so that the latter and shaft 19 are actuated. During this movement, the parts are shifted from the position shown in Fig. 6 to that shown in Fig. 5, and it is noted that the offset 37 of the spring-held swinging arm 36 engages the edge of the coin and prevents it from jumping or being jarred from position between

the studs 32 and 21. The guide lug 35 is so shaped that, at the end of the forward movement of the shifter and operating arms, it forces the coin from between the studs 32 and 21, and then the stud 32 moves the coin from the position shown in full lines in Fig. 5 to that shown in dotted lines, so that the operating arm 20 and shaft 19 are free to be returned to normal position by the spring 23, and as this occurs the coin drops through the discharge chute 14 as indicated by arrows in Fig. 5.

To prevent the actuation of the operating shaft 19 through the medium of an annular check or washer, a switching device or deflector is provided. This switching device 44 is formed of a piece of stamped, bent sheet metal and is most clearly shown in Figs. 1 and 3. It is pivoted intermediate its ends to a support 45 which in turn is pivotally mounted on the back plate 11. As shown, the support 45 is U-shaped and is provided with offset ears 46 at its ends and the deflector or switching device is provided with corresponding offset ears disposed between the ears 46 of the U-shaped support 45 and connected thereto by a pin 47. This pin and the stud 48, upon which the support 45 is pivotally mounted, are disposed at right angles so that the deflector 44 is movable in two different directions, that is to say, both to and from the plate 11, and also in a direction parallel with the plate. A spring 49 connected to the support holds it and the deflector in normal position with the support engaging a stop 50 formed on the back plate 11. A spring 51 coiled about the pivot pin 47 presses the forward end of the deflector toward the plate and tends to move an offset finger or prong 52 on the deflector through an opening 53 in the back plate and into the coin chute. Normally the forward end of the deflector is held out of the coin chute by a trip device 54.

This trip device is most clearly shown in Fig. 2, and is in the form of a bell-crank. It is pivotally mounted at its lower end upon a lug 55 on the back plate 11 and is provided with a long, upwardly extending vertical arm which extends through a guide slot in a bracket 56 fixed to the plate 11. The short horizontal arm of this trip device extends through a slot 57 in the front plate and is engaged and held in normal position by the part 25 of the shifter arm. In this normal position, the trip 54 engages the tail 58 of the deflector and holds it in normal position against the tension of the spring 51 with the prong 52 at its forward end withdrawn from the coin chute. During the initial limited forward movement of the shifter arm, the trip 54 is released and swings by gravity away from the plate 11, so that the deflector is free to be shifted by the spring 51. Then, the prong 52 at its forward end will engage a coin in the arrested position, but will not inter-

fer with the operation of such coin in the manner previously described. But if an annular check or washer has been inserted and arrested by the stud 32 and lug 35, the prong 52 at the forward end of the deflector will enter the central opening of such a check or washer and pass therethrough into a depression 59 (see Fig. 3) formed in the front plate.

When this occurs, the continued forward movement of the shifter arm and stud 32 will not move the check against the stud 21 of the operating arm, but instead the washer and deflector 44 will be moved from the position indicated in Fig. 1 to that shown in Fig. 6. In other words, the washer will be swung from the position indicated at *a* to that shown in full lines at *b*, and such an annular check or washer will be rendered ineffective to actuate the operating shaft 19. Upon the further forward movement of the stud 32 from the position shown in full lines in Fig. 6, the washer and deflector will drop back to their original position. Then, upon the return movement of the shifter arm, the stud 32 will engage the washer and remove it from the finger 52 so that it will pass out through the discharge chute 15, as indicated by the arrows in Fig. 6. It is noted that the prong or finger 52 is rearwardly inclined so that the forward movement of the stud 32 cannot disengage an annular check from the finger, but such stud, upon its rearward movement will readily disengage it and, as stated, deflect it out through the chute 15.

To prevent disengagement of the washer from the deflector as the latter is swung from the position shown in Fig. 1 to that shown in Fig. 6, the extension 58 of the deflector, during this movement, is disposed outside of an offset piece 60 mounted on the back plate 11. With this arrangement, the deflector can only swing on its pivot pin 47 when in normal position, and cannot be swung to release the annular check or washer as it is moved between the positions indicated in Figs. 1 and 6.

The front plate 10 is provided at its lower end with perforated feet or flanges 61 by which the mechanism can be mounted on a suitable base. The segmental portion 25 of the shifter arm is provided with ratchet teeth which cooperate in the usual way with a full-stroke dog 62.

The improved mechanism is simple in construction, effectively prevents the operation of the apparatus by annular checks or washers or other penetrable lugs and ejects coins and annular checks through separate discharge openings. Changes may be made in the details set forth without departure from the scope of the invention as defined in the appended claims.

I claim as my invention:

1. In a coin-controlled apparatus, an operating member, a shifter arranged to engage

and move inserted coins and checks edgewise and to actuate said member through the medium of interposed coins, and a switching device arranged to engage apertured checks and deflect the same as such checks are advanced edgewise by said shifter, whereby such checks are rendered inoperative upon said member.

2. In a coin-controlled apparatus, an operating member, a switching device for engaging inserted apertured checks and a manually operable shifter for actuating said member through the medium of an interposed coin, said shifter being arranged to actuate said switching device through the medium of an interposed apertured check to thereby render such check ineffective.

3. In a coin-controlled apparatus, an operating member, a deflector for engaging inserted apertured checks, a shifter having a part arranged to engage and move inserted coins through one path to actuate said member, and said shifter part being arranged to engage and move apertured checks engaged by said deflector through a different path.

4. In a coin-controlled apparatus, a coin-chute, a deflector for engaging inserted penetrable checks, a manually operable shifter having a part arranged to engage and eject inserted coins through one path, said shifter part being arranged to engage and eject checks engaged by said deflector through a different path, and a member interposed in the path of movement of the coins and actuated thereby.

5. In a coin-controlled apparatus, a coin-chute, a shifter for moving inserted coins and checks edgewise and for ejecting the same, and a pivoted switching device for engaging penetrable checks, whereby the latter and inserted coins are moved through different paths by said shifter.

6. In a coin-controlled apparatus, a coin-chute, a reciprocating shifter arranged on its forward stroke to move inserted coins in a predetermined path and eject the same, and a switching device for engaging penetrable checks to deflect the same from such path as they are moved by said shifter, the latter being arranged, on its return stroke, to engage and eject such checks.

7. In a coin-controlled apparatus, a coin-chute having means for guiding inserted coins edgewise, an oscillating shifter arm, an oscillating operating arm arranged to be actuated on the forward stroke of said shifter arm through the medium of an interposed coin, and a fixed stop in said chute cooperating with said shifter arm to arrest the inserted coins and arranged to force the interposed coin from between said arms at the end of the forward stroke of said shifter arm.

8. In a coin-controlled apparatus, a shifter for engaging and moving inserted coins and checks, a switching device and a shiftable support whereon said switching device is

movably mounted to thereby permit the movement of said device in one direction into and out of engagement with inserted coins and checks and in another direction to deflect penetrable checks and render the same ineffective.

9. In a coin-controlled apparatus, a manually operable shifter, a member actuated thereby through the medium of an interposed coin, and a deflector cooperating with said shifter and mounted to move in two different directions at an angle to each other to thereby engage and deflect inserted penetrable checks.

10. In a coin-controlled apparatus, a manually operable shifter for engaging and moving inserted coins, a member operated by said shifter through the medium of coins moved thereby, a pivoted deflector operated by said shifter to move into and out of engagement with inserted coins and checks, and a pivoted support wherein said deflector is mounted, said support and deflector being operable by said shifter through the medium of an interposed apertured check, to thereby deflect the latter and render the same ineffective.

11. In a coin-controlled apparatus, a coin-chute, an oscillating shifter arm, an oscillating operating arm actuated by the forward stroke of said shifter arm through the medium of an inserted coin, and a switching device for engaging inserted apertured checks and operated on the forward stroke of said shifter arm through the medium of the engaged annular check to deflect the latter and render it ineffective upon said operating arm, said shifter arm being arranged to engage and eject an apertured check upon its return stroke.

12. In a coin-controlled apparatus, a coin-chute, an oscillating shifter arm for engaging and moving coins in a predetermined path upon its forward stroke, an operating member actuated thereby, a fixed stop cooperating with said shifter arm to arrest inserted coins and to eject the same at the end of the forward stroke of the shifter arm, a switching device for engaging inserted apertured checks and cooperating with said shifter arm to deflect and render the same ineffective upon the forward stroke of said shifter arm, the latter being arranged to engage and eject apertured checks upon its return stroke.

13. In a coin-controlled apparatus, a coin-chute having two discharge openings, a shifter arranged to move inserted coins edgewise through said chute and eject the same through one of said chute openings, an operating member actuated by the coins so moved, and a switching device for engaging inserted apertured checks and arranged to cooperate with said shifter to deflect the same, said shifter being arranged to move

such checks edgewise and to eject the same through the other of said chute openings.

14. In a coin-controlled apparatus, a coin-chute having means for guiding coins edgewise, oscillating shifter and operating arms mounted on opposite sides of said chute and having lugs extending into the same to effect the operation of said operating arm by the forward stroke of said shifter arm through the medium of an interposed coin, and a fixed guide in said chute cooperating with the lug of said shifter arm to arrest the inserted coin and to eject the same from between said lugs at the end of the forward stroke of said shifter arm.

15. In a coin-controlled apparatus, a coin-chute having means for guiding coins edgewise, oscillating shifter and operating arms mounted on opposite sides of said chute and having lugs extending into the same to effect the operation of said operating arm on the forward stroke of said shifter arm through the medium of an interposed coin, means for ejecting the coin from between said lugs at the end of the forward stroke of said shifter arm, and an oscillating switching device arranged to engage inserted apertured checks and deflect the same out of the path of the lug of said shifter arm during the forward stroke of such arm, the shifter arm lug being arranged to engage and eject such checks upon the return stroke of said arm.

16. In a coin-controlled apparatus, a manually operable shifter, a latch held inoperative by an inserted coin or check and arranged, in the absence of a coin or check, to arrest said shifter after a limited initial movement, and a deflector normally held out of the path of an inserted coin and arranged to be shifted by the limited initial movement of said shifter into engagement with an inserted coin or check, said shifter being arranged to move an inserted coin through a predetermined path and to cooperate with said deflector to move an inserted apertured check through a different path.

17. In a coin-controlled apparatus, oscillating shifter and actuating arms concentrically pivoted and having cooperating abutments arranged to engage an interposed coin to effect the operation of the actuating arm on the forward stroke of the shifter arm, and a pivoted switching device arranged to engage and deflect apertured checks and the like out of the path of the shifter arm abutment and then return the same to such path, whereby such checks are rendered ineffective upon the forward stroke of the shifter arm and are engaged and ejected by the abutment of the shifter arm on its return stroke.

18. In a coin-controlled apparatus, a shifter for moving inserted coins and checks, a switching device, and a movable support whereon said switching device is movably mounted, whereby said device is movable in

one direction into engagement with inserted coins and checks, and in another direction to deflect penetrable checks and render the same ineffective.

- 5 19. In a coin-controlled apparatus, a coin-chute, a shifter arranged to engage and advance inserted coins and checks and to eject the same, and a switching device arranged to engage and deflect annular checks as such checks are advanced by said shifter whereby inserted annular checks and coins are moved through different paths by said shifter.
- 10 20. In a coin-controlled apparatus, a coin-chute, a shifter for moving inserted coins and checks and a switching device for engaging annular checks and deflect the same as they are moved by said shifter whereby the latter and inserted coins are moved through different paths by said shifter.
- 15 21. In a coin-controlled apparatus, a coin chute, a shifter arranged to engage in advance inserted coins and checks through said chute and to eject the same therefrom, a latch controlled by coins and certain checks for normally preventing the operation of said shifter, a switching device arranged to engage penetrable checks as they are advanced by said shifter and deflect the same, whereby such checks and coins are advanced by said shifter through different paths, and an operating member interposed in the path of movement of the coins advanced by said shifter and actuated thereby.
- 25 22. In a coin-controlled apparatus, shifter mechanism for moving inserted coins and checks, and a cooperating switching device mounted to move laterally into and out of engagement with the inserted coins and checks, and said switching device being movable vertically to deflect annular checks engaged thereby and render the same ineffective.

EMERY MIHALEK.
